GOVERNOR FOR TURBINES

William J. Pugh, East Milton, Mass.

Application September 3, 1935, Serial No. 39,005

2 Claims. (Cl. 253—144)

This invention relates to turbines which may be readily and economically installed and of the character employing a turbine runner and a deflecting guide therefor, and has for the primary object the provision of a load control means for automatically governing the power development of the device by controlling the guide to vary the fluid deflection to the turbine runner and thereby automatically vary the output of power proportionately to the load on the device.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation, partly in section, illustrating a turbine constructed in accordance with my invention.

Figure 2 is a top plan view illustrating the same.

Figure 3 is a fragmentary horizontal sectional view showing a brake mechanism.

Figure 4 is a top plan view illustrating the application of the turbine to a stream or body of water.

Figure 5 is a fragmentary vertical sectional view showing the same.

Referring in detail to the drawings, the numeral 1 indicates a stream or any other body of water and traversing said stream is a dam 2 forming a part of a turbine 3 driven by the force of the water. The dam and turbine form a single unit and the installation of the unit to the stream or body of water is extremely simple and economical as will be apparent from Figures 4 and 5 of the drawings. The turbine includes a vertically arranged cylindrical casing 4 to which the dam units are secured. The upper end of the casing 4 is closed by a removable cover 5 forming a journal for a vertically arranged turbine shaft 6. The shaft 6 projects well into the casing and has secured to its lower end a turbine runner 7 of a conventional construction. The casing 4 is equipped with a screened inlet 8 to admit water from the stream to the runner 7 for bringing about rotation of the shaft 6. The flow of water through the inlet 8 is controlled by a sliding gate 6' equipped with an operating means 7' of any conventional construction.

A tubular shaft 9 is journaled on the shaft 6 within the casing and its lower end has secured thereto a turbine guide 10 of the conventional construction. The guide 10 acts as a medium for

deflecting water to the runner 7 and by varying the deflection of the water to the runner, power developed by the device may be varied. The guide 10 is capable of turning or rotating and its direction of rotation is opposite to that of the turbine runner.

Located in the casing 4 and secured to the tubular shaft 9 is a brake drum 11 having associated therewith brake shoes 12. The brake shoes are journaled on a stub 13 secured to the cover 5. The free ends of the shoes are engaged by a cam 14 and are held in engagement therewith by a spring 15 connecting said shoes. The cam is secured to a shaft 16 supported by a journal 17 carried by the cover 5. An arm 18 is secured to the shaft 16 and has connected thereto a governor mechanism 19. The governor mechanism is of a conventional ball type construction and is secured to and driven by the shaft 6. The governor mechanism also includes in its construction a spring 20, one end of which seats against the sliding yoke 21 of the governor and the other end against the collar 22 adjustably secured to the shaft 6. The collar 22 permits the tension of the spring 20 to be varied and consequently provides means for varying the action of the governor mechanism. A bell crank lever 23 is connected to the governor yoke 21 and to a link 24 which is in turn connected to the arm 18. The bell crank lever is pivotally mounted to a bracket 25 carried by the cover 5. A dash pot 26 is carried by the cover 5 and is connected to the link 24 and includes in its construction a compensation spring 27. The governor mechanism is driven by the shaft 6 and acts to apply and release the brake shoes 12 from the drum 11. The brake shoes 12 when applied to the drum 11 prevent rotation of the guide 10 of the turbine and the holding of the guide against rotation provides a greater deflection of fluid to the turbine runner, consequently permitting maximum power development by the latter. It is to be understood that the rotation of the guide is due to the action of the force of water thereon. The governor mechanism is so connected with the brake shoes that an increased speed of the shaft 6 brings about a release of the brake shoes from the drum, allowing the turbine guide to rotate or turn under the influence of the water, and reducing the power developed by the turbine runner, which brings about a slowing down of the latter. As the load increases on the shaft 6, the speed of rotation thereof decreases and the governor's action is reverse or brings about application of the brake shoes to the drum and thereby prevents turning of the guide 10 for

increasing the angle of deflection of water to the turbine runner and thereby increases the power output from the latter.

While this invention is described as especially adaptable for propulsor by water force, it is to be understood that its application is readily adaptable for turbines operated from air or gas pressure or any other fluid pressure.

Having described the invention, I claim:

- 10 1. A turbine including a casing having located therein a turbine runner and a deflecting guide therefor to control the power output of said turbine runner, a shaft secured to the runner and journaled to the casing, a tubular shaft journaled 15 on the first shaft and connected to the guide, a brake drum secured to the tubular shaft, a brake mechanism engageable and disengageable with the drum and supported by the casing, and a

governor supported by said casing and connected to the brake mechanism and to the first shaft.

2. In a turbine, a casing having a turbine runner therein and a deflecting guide for the latter rotatable in a direction opposite to the direction 5 of rotation of the runner, a shaft secured to the runner, a tubular shaft journaled on the first shaft and secured to the guide, a brake drum secured to the tubular shaft, brake shoes to engage and disengage with the drum and supported by 10 the casing, an operating means for said brake shoes carried by the casing, and a governor connected to the operating means and to the first shaft for controlling the deflecting guide for increasing and decreasing the power output by said 15 turbine runner.

WILLIAM J. PUGH.
